SLIP LASTED PLATFORM SHOE

Leo B. Hollander, Sullivan, Mo.

Application September 28, 1946, Serial No. 700,033

1 Claim. (Cl. 36—19.5)

1

This invention relates generally to shoes, and particularly to slip lasted shoes.

While the manufacture of shoes according to the slip lasted process has been practiced on a substantial scale, it is a recognized fact that such shoes are neither ruggedly constructed nor of long life. These frailties are attributable, in the main, to the fact that as heretofore practiced it has been necessary to utilize relatively weak, thin and flexible material, and such has been deemed essential to the economical practice of the slip lasting process.

The object of the present invention, generally stated, is to provide a slip lasted shoe which may be conveniently made of materials of heavier and stronger gauge than those heretofore employed in the making of such shoes.

Another object of the invention is to improve the mode of assembly of the several parts entering into the construction of slip lasted shoes.

Further objects will become apparent to those skilled in the art when the following description is read in connection with the accompanying drawings in which:

Figure 1 is a view in side elevation of an assembled upper suitable for use in accordance with the present invention;

Figure 2 is a plan view of the insole of a slip lasted shoe constructed in accordance with the present invention;

Figure 3 is a view in side elevation of the parts shown in Figures 1 and 2 assembled together, part being torn away to reveal the relationship to the parts;

Figure 4 is a partial sectional view taken along line 4—4 of Figure 3;

Figure 5 is a view in side elevation showing the next step of assembling the shoe;

Figure 6 is a bottom view of the finally assembled parts shown in Figure 5;

Figure 7 is a view in side elevation of the complete shoe; and

Figure 8 is a view corresponding to Figure 1, but showing the modified form of the upper.

In accordance with the present invention, generally stated, the upper of a slip lasted shoe is provided with a marginal extension sufficient to embrace not only the usual upper and its lasting allowance, but also sufficient to cover the side walls of a platform or midsole member to be assembled therewith. At the datum in said upper to be occupied by the insole, a row of perforations is preformed. A row of correspondingly spaced perforations is likewise provided adjacent the margin of the insole member to be utilized. The

invention is characterized by the feature that the insole member, which corresponds in position in the shoe to the part usually denominated the sock liner of a slip lasted shoe, is made of substantially heavier gauge material than the customary sock liner, as for example, 1-3 iron leather. Having thus provided the pre-perforated insole and upper members, the former is assembled within the latter and connected thereto by a strong leathern thong interlacing the perforations in the respective parts. Preferably the thong is lock stitched with a suitable strand on the interior of the assembly.

As pointed out above, the upper is provided with considerable excess substance downwardly below the datum of its connection to the insole. Such excess substance provides a pocket within which a suitable platform or midsole member may be received and the excess upper material then drawn taut about the edges of the midsole member and secured to the bottom surface thereof, whereby not only to cover the midsole, but to connect the same to the upper.

Referring now to the drawings for an illustrative embodiment of the invention, an upper 1 is cut according to any chosen pattern, but in addition to including the parts usually embraced by the upper with its lasting allowance, includes also a marginal increment corresponding to the thickness of the platform or midsole member to be employed. The upper 1 is provided with a row of spaced perforations 2 defining the datum of the insole of the shoe. The lasting allowance of the upper is represented by the area embraced between the dotted line 3 and the lower margin 4 thereof. The area embraced between the dotted line 3 and the row of perforations 2 corresponds substantially to the thickness of the midsole member to be utilized in connection therewith.

An insole 5 of strong leather, such for example as 1-2 iron, is provided with a row of perforations 6 extending about the margin thereof. Perforations in row 6 of sole 5 correspond in size and spacing to the perforations of row 2 in the upper 1.

If desired, a suitable lining for the upper, as well as a box toe and premoulded counter may be provided with perforations corresponding in size and placement to those of the upper 1 and the insole 5.

The upper 1 is suitably assembled with a lining 7, if desired, and appropriate box toe 8 and a counter 9, all said parts being arranged so that the perforations therein at the datum of the in-

sole substantially align. The insole 5 is then arranged with its perforations 6 aligning with the perforations 2 of the upper and a thong 10 laced through the perforations. In the embodiment shown, the thong is lock stitched from the outside with a heavy cord 11 engaging the loops of the thong as the latter extend through the perforations to the inside of the downturned marginal portion of the insole, as shown clearly in Figure 4. The thong 10 thus extends lengthwise about the shoe and exerts a peripheral force tending to constrict the upper at the datum of the insole.

When thus assembled the marginal excess of upper material provides a pocket within which a midsole member 12 may be inserted. In the embodiment shown the midsole 12 is of the platform type being a block of wood constituted to provide not only the forepart but also the shank and heel part of the midsole. It will be understood, however, that the midsole may be less extensive or built up of a plurality of parts. If desired, the midsole 12 may be cemented to the bottom face of insole 5, but such is not essential to the invention. With the midsole 12 properly emplaced in the pocket defined by the margins of upper 1, the latter may be drawn taut about the edge of the midsole 12 and laid over the bottom of the midsole and secured thereto by cement or other suitable fastenings after the fashion of lasting the upper over an insole in the usual process of shoe manufacture. As seen clearly in Figure 6, the lasting allowance of the upper represented as between the dotted line 3 of Figure 1 and the margin 4 thereof is secured to the bottom of midsole 12.

The shoe is then completed by the application of a suitable wear sole 13 in any desired manner.

While in the embodiment just described, the upper 1 is a one piece upper embracing not only the usual upper portion, but the lasting allowance, and in addition an area for embracing the edges of the midsole, it is not essential that the upper 1 be composed of a single piece of leather. In accordance with the usual practice in shoe making, the upper may be longitudinally divided or it may be composed of separate vamp and quarter sections, or as shown in Figure 8, the upper may consist of a top section 21 and a lower section 22 secured together by line of stitching 23, so that together the parts 21 and 22 constitute not only the usual upper and its lasting allowance, but also the portion for covering the edge of the midsole. The composite upper shown in Figure 8 is assembled with the other parts in the manner hereinbefore described.

From the foregoing description those skilled in the art will understand the construction of the shoe and realize that it accomplishes its objects. Not only does the construction enable the utilization of heavier and stronger insoles and insole

connections than have hitherto been possible in slip lasting shoes, but the utilization of a leathern thong as the connecting means between the insole and the upper contributes to the ornamental effect of the shoe, particularly if the thong is of contrasting color to the adjacent upper, and, moreover, the peripheral force exerted by the thong to constrict the upper about the insole datum enables the production of a slip lasted shoe having a fine finished appearance, which is difficult, if not impossible, of achievement in the usual methods of constructing slip lasted shoes.

While the full disclosure has been given of one embodiment of the invention and alternatives have been suggested, it is not to be understood that the invention is limited to the details of construction shown and described. On the contrary, many modifications and variations of the structure will immediately present themselves to those skilled in the art without departing from the spirit of the invention, or the scope of the appended claim.

Having thus described the invention, what is claimed and desired to be secured by Letters Patent is:

A shoe comprising an upper, an insole, means for joining the upper and the insole, and a midsole, said upper having a series of perforations extending around its lower marginal portion a sufficient distance inwardly to provide an extension covering the edge of the midsole, said insole having a downturned marginal portion with a series of perforations extending therearound and arranged in alignment with the perforations of the upper, and said means for joining the upper and the insole including a thong extending around the outside of the upper and having a plurality of inwardly directed loops passing through the respective aligned pairs of perforations, and a cord passing through the loops on the inside of the downturned marginal portion of the insole to lock said loops in place.
